ADVERTISING DISPLAY SUPPORT FOR PRICE PANELS

Gross W. Wood, San Francisco, Calif., assignor to
Raymond George L'Esperance, Mill Valley, Calif.

Filed Apr. 16, 1958, Ser. No. 728,914

3 Claims. (Cl. 40—11)

This invention relates in general to advertising support means for retail merchandise and particularly to wire clip advertising supports useful in combination with the price marker strip ordinarily facing the front edges of store shelves.

Merchandising on the retail level and methods of presenting goods to customers and the public generally have radically changed in recent years. The heritage of the general store with unmarked open boxes and barrels, hardware hung in the rafters, and unreliable labels on tins and clothing has given way to a fiercely competitive battle for the consumer dollar. Order houses from which housewives used to order their daily supplies without having seen any merchandise at all have been replaced by serve-yourself markets wherein every conceivable attempt is made to bring different articles to the customer's attention and inspection. Merchandising becomes, in many cases, display merchandising with numerous signs, exhibits and announcements, all competing for attention.

Where merchandise is stored on open shelves, as in the modern market, with a minimum of space for each item within a group of related items, the use of advertising displays, special product information, notification of special prices, etc., poses a problem. There is not enough space available on the shelf for signs displaying such information without interference with the product or the ready removal thereof from the shelves. Further, loose sign holders and signs are easily pushed off the shelf or displaced upon another shelf by a careless customer. Sign holders held by clamps over the edges of shelves have a degree of permanence, but tend to wobble and mar the shelves so that they must be periodically refinished. Price inserts held in retainer grooves on shelf edges are too small to contain printed descriptive matter and sometimes even the use of red numerals instead of black numerals, to indicate special prices goes unnoticed.

The advertising display support disclosed herein is for use with price panels, markers, or other advertising matter, and comprises a wire clip advertising support for retention in the retainer grooves used for holding price markers on the front edges of store shelves. The wire display support is formed from a single piece of stiff spring wire and has a planar open loop base member slightly larger in diameter than the distance between the retainer grooves. One end of the loop has a straight portion constituting a line of reference, as will later appear. By compressing the loop, it can be made to fit into the grooves and bear against them, the straight portion engaging one groove and serving to hold the wire clip in a single position. At the outward end of said straight portion the wire is bent inward of said loop for a distance sufficient to clear the retainer grooves, and then further bent upward and outward from said loop and retainer grooves. The wire terminates in an elongated hook or other means suitable for holding advertising or promotional material such as a laminated panel or other card containing information concerning merchandise. Because only spring wire is

2

required in the construction of the wire clip element, the clip may be manufactured very cheaply. Since the wire is held by the spring action therein, there are no moving parts and price panels may be very quickly and simply mounted. The display support may be used in combination with different sizes and types of display cards, from which adaptation to any type of display is possible.

Accordingly, an object of the invention is to provide a novel display support for supporting advertising matter, 10 display panels, price markers, and the like from the price panel on the front edge of store shelves.

A further object of the invention is to provide an advertising spring wire display support for store shelves which snaps into position and is securely retained in the 15 price marker grooves on the front edges of the shelves.

Another object of the invention is to provide an advertising display support comprising a spring wire clip member for snap engagement in the retainer grooves of the metallic facing generally provided for price markers on 20 the front edges of store shelves.

Another object of the invention is to provide an advertising support integral with a spring wire display support member, the latter being formed for snap-fixed engagement in a grooved retainer, such as generally provided for 25 price markers on the front edges of store shelves.

Further objects are to provide a construction of maximum simplicity, economy, and ease of manufacture, also such further objects, advantages and capabilities as will fully appear and as are inherently possessed by the device 30 and the invention described herein.

Invention further resides in the combination, construction and arrangement of parts illustrated in the accompanying drawings, and while there is shown therein a preferred embodiment thereof, it is to be understood that the 35 same is merely illustrative of the invention and that the invention is capable of modification and change, and comprehends other details of construction without departing from the spirit thereof or the scope of the appended claims.

40 The invention will be better understood upon consideration of the following description and figures, in which:

Figure 1 is a front elevational view of the advertising display support engaged in a price panel and showing the method of attachment of the wire loop within the grooves 45 of said panel;

Figure 2 is a side elevational view of the spring wire advertising display support along the line II—II of Figure 1;

Figure 3 is a front elevational view of the spring wire 50 display support;

Figure 4 is a side elevational view of the spring wire display support of Figure 1;

Figure 5 is a front elevational view of an alternate embodiment of the advertising display support engaged 55 between the grooves of the price panel, in which the axis of the wire loop is horizontal with respect to and parallel with the grooves of the price panel; and

Figure 6 is a side elevational view of the spring wire advertising display support shown in Figure 5, taken along 60 line VI—VI thereof, and looking in the direction of the arrows.

Referring now to the drawing and especially to Figures 1 and 2 thereof, there is shown generally a spring wire display support 11 mounted in position between parallel 65 price retainer grooves 12 and 12a secured to the edge of shelf 14. The retainer grooves 12 and 12a may be of any type but usually they are made integral in an extrusion 15 which forms a facing for the front edge of market shelves. Such extrusions are well known and are in practically universal use. The spring wire display support 11 is composed of stiff spring wire, preferably steel, such as

piano wire, which has considerable integrity even in small diameters. The entire wire display support is formed from a single piece of wire, and comprises a loop portion 16 terminating in an open and unconnected end 17, and a card or other supporting means 18 extending angularly outward and terminating in an elongated loop for example, as a card support 26 at the other end, all as will be described in detail hereinafter. Loop 16 is generally planar beginning with end 17, continuing in substantially a parabolic curve 23 to a straight portion 20, thence at right angles thereto in a straight portion 22 and thence downwardly in a short portion 19, parallel to portion 20 and a sufficient distance to clear the retainer groove 12 and 12a and thence angularly outward along portion 18, terminating in means 26. In the display support shown in Figures 1 to 4, inclusive, the axis of the curve 23 is perpendicular to the parallel retainer grooves 12 and 12a.

Possibly, in order to obtain better spring action, it may be desirable to have the axis of the loop 23 at right angles to the line of the parallel retainer grooves 12 and 12a as shown in Figures 5 and 6. Here the end 17 is designed for substantial parallel bearing in the groove 12, continuing in the parabolic curve 23 to straight portion 20, thence to a relatively short inturned portion 19a extending a sufficient distance upwardly to clear the groove 12a, and thence upwardly and outwardly as before described.

Card supporting means 18 may be a straight member 24, as shown, with an elongated hook member 26 on the end thereof, or other means for affixing cards or signs to said wire display support 11. The hook embodiment 26 is easily formed to stand rigidly in either a vertical plane (see Figures 2 and 4) or an inclined plane (see Figure 6) for reception and retention of a card or laminated panel 27 slotted along its planar dimensions. The angle of the hook element with respect to the loop 16 may be varied to suit particular conditions, i.e., 45°.

Card supporting means 18 is preferably a continuation of the planar portion 19 or 19a of the loop 16 by an integral wire section 21, which bends at 28 away from the end 19 at an angle inwardly of loop 16 and generally along the same plane thereof to avoid the groove 12. Section 21 bends at the other end thereof outwardly from loop 16 at 29. Bend 29 may be a simple outward bend 31 as shown in Figures 5 and 6, or a reverse and outward bend 32 particularly as shown in Figures 1 and 3. The reverse and outward bend 32 tends to be somewhat stronger because of the twisting action as the springy card supporting means is deflected downward.

In operation the distance across loop 16 from the straight portions 22 of Figure 1 and 20 of Figure 5 to the opposing side at 17 is slightly greater than the distance between the retainer grooves 12 and 12a. By compressing the loop 16 it can be forced between grooves 12 and 12a with straight portion 22 engaging either groove. Upon release of the loop the spring action forces the straight portions 22 of Figure 1 and 20 of Figure 5 and opposing side 23 to bear against one of the grooves, the latter thereby holding wire element 11 in place and against any rotative movement. Grooves 12 and 12a will ordinarily be disposed one above the other and from such plane, card supporting means 18 will project outwardly and upwardly. However, in some instances the front edge of the shelf is slanted inwardly at the top, so that when used under such conditions the projection 18 will stand more vertically upward.

Obviously, it takes only an instant to remove the advertising display support from the grooves. In the form shown in Figure 1 all that is necessary is to pull down-

wardly on the means 18 against the spring of the open member 17 and the clip is released from engagement with the groove 12, while in the form shown in Figure 5, the pull is upwardly.

While the invention has been disclosed with respect to several preferred embodiments, it will be apparent to those skilled in the art that numerous variations and modifications may be made within the spirit and scope of the invention and thus it is not intended to limit the invention except as defined in the following claims.

I claim:

1. An advertising display support for spring engagement between the parallel grooves of a price receiving panel, formed of a single piece of spring wire or the like, comprising in continuous integral combination, a loop portion having two legs and a curvature of approximately 180° therebetween, the tangent of which curvature bears in one of the grooves of a price receiving panel, one leg of said loop portion being a free end and spaced from every other portion, a substantially straight portion extending from and at right angles to the other leg of said loop portion for engaging in the opposite groove of said price receiving panel, a segment extending inwardly at right angles to said straight portion and generally toward the said free end, said loop, straight portion and segment all lying in the same plane, and an angularly outwardly disposed advertising support means extending from said segment, said straight portion being resiliently compressible against said loop portion for quick release from its bearing in the groove of the price receiving panel.
2. An advertising display support for spring engagement in the oppositely disposed parallel grooves of a store shelf price tag molding, comprising in combination a parabolic loop portion having two legs, one of said legs being a free end and spaced from every other portion, for engagement in one of the grooves of a price tag molding, the other of said legs being a relatively straight portion for engagement in the opposite groove of said price tag molding, a segment extending inwardly from said straight portion and substantially at right angles thereto, said loop, leg portions and segment all lying in the same plane, and a supporting portion having a terminal hook, extending from said segment in a different plane, all of said portions being formed from a single continuous piece of spring wire or the like.
3. An advertising display support for spring engagement in the oppositely disposed parallel grooves of a store shelf price tag molding, comprising in combination a parabolic loop portion having two legs, the axial tangent of said loop bearing in one of the grooves of the price tag molding, one of said legs being a free end and spaced from every other portion, the other of said legs having a straight portion extending therefrom at right angles inwardly for engaging in the opposite groove of said price tag molding, a segment extending inwardly from said straight portion and substantially at right angles thereto, said loop, leg portions, straight portion and segment all lying in the same plane, and a supporting portion extending from said segment in a plane different from the first mentioned plane, all portions of said combination being a single continuous piece of spring wire or the like.
